Atty.

UNITED STATES PATENT OFFICE

JOHN T. JANETTE, OF CHICAGO, ILLINOIS

SELF PRIMING PUMP

Application filed April 18, 1930. Serial No. 445,408.

This invention relates in general to a pump priming device, and has more particular reference to a rotary pump, and to rotary driving mechanism for a pump.

One of the principal objects of the invention is in the provision of means for storing a liquid during the action of a pump, which is used for priming the pump when the driving mechanism therefor is actuated after stopping the pump.

A further object of the invention is in the provision of means for providing a liquid seal for a pump which is automatically actuated when the pump driving mechanism is operated.

A still further object of the invention is in the provision of a liquid seal for the discharge side of a pump which allows the escape of air therethrough; so that the pump in operation will tend to form a vacuum which will lift the liquid to be pumped from a remote container, and thereby draw the liquid therethrough in the ordinary manner.

A further object of the invention is in the provision of a pump priming means which will maintain the priming liquid in a position where it cannot be withdrawn through the pump and sucked back into the liquid container, but will be ready for use whenever the operating mechanism is started.

Other objects of the invention will appear hereinafter, the accompanying drawings illustrating a preferred embodiment of the invention.

In the drawings Fig. 1 is a side elevation, with many of the parts shown in section, of a pump mechanism illustrating this invention; Fig. 2 is a sectional view taken on the line 2—2 of Fig. 1; and Fig. 3 is a detail view illustrating a modification.

In the operation of a pump for supplying liquid, it is frequently found that when the pump stops, the liquid in the pump, or on the intake side of the pump flows, or is sucked backwardly into, the receptacle from which it was pumped; leaving the pump dry or without sufficient liquid in the pump mechanism to form an air seal or to act as a primer when the pumping mechanism is again actuated.

The present invention is designed to provide a priming device in which a reserve of liquid is contained sufficient to form a liquid seal for the pump as soon as the pump is started, the liquid being contained in a receptacle from which it is thrown or discharged when the pump driving mechanism is actuated.

Referring now more particularly to the drawings, a pump mechanism is shown mounted in a receptacle 4, which has a discharge outlet 5. In the receptacle is a casing 6, having discharge openings 7 adjacent the upper end, with a pump 8 secured to the bottom of the casing and communicating, for pumping liquid to the casing, through a pump discharge opening 9.

The pump may be of any suitable type, and is shown as operated by a vertical shaft 10, having a detachable clutch 11 at its upper end for connecting it with the shaft 12 of a motor 13, which is mounted at the top of the casing 6 by means of a suitable support 14.

The pump may consist of any suitable pumping mechanism, as for an example a pair of meshing gears 15 and 16, one of which is secured to the shaft 10 by means of a key 17, the gears fitting closely and through part of their periphery in a casing 18, which has an inlet chamber 19 at one side, and an outlet chamber 20 at the other side of the gears. The outlet 20 communicates with the opening 9 in the bottom of the casing, and a liquid inlet pipe 21 is connected to the inlet chamber 19 of the pump casing. The pipe 21 extends outside of the receptacle 4, and is provided if desired with a strainer 22, which has a priming vent 23, the strainer in turn being connected by means of a pipe 24 to a source of liquid supply, which may be at some distance from the pump and below the level thereof.

Attached to the pump driving shaft is a receptacle 25, preferably annular in shape, and having a central hub portion 26, of the same height as the outer edges 27 thereof, to form a ring-shaped container which rotates with the shaft to which the hub portion may be connected by pressing it tightly thereon or by means of a pin or rivet 28.

When the pump is operated by means of the motor 13, liquid is drawn through the pipes 24 and 21, and discharged from the chamber 20 through the opening 9, filling the base of the casing 6 until the liquid pumped is discharged through the opening 7 into the container 4. When the pump is stopped the liquid in the casing 6 below the opening 7 may drain backwardly through the pump 10 and through the pipes 21 and 24, but an amount of liquid to fill the receptacle 25 will be retained therein. Even though the pump is drained dry of liquid, this priming receptacle 25 will still hold an amount sufficient to prime the pump when the pump driving mechanism and the pump is again started. This liquid will be thrown out of the priming receptacle 25 as soon as the driving motor 13 is started, the liquid draining through the 20 opening 9 in the bottom of the casing 6 and filling the discharge chamber 20, thereby forming a liquid seal which prevents air from passing through the pump in a reverse direction, and causes the pump to discharge air 25 through the liquid seal tending to form a vacuum in the inlet chamber 19 and the supply pipes connected therewith.

Instead of having the receptacle secured to the shaft as shown in Fig. 1, a circular receptacle 30 may be secured in the casing 6, as shown in Fig. 3, the shaft 10 carrying an arm or agitator 31, which engages the liquid in the receptacle 30, and discharges it therefrom when the motor is operated for priming 35 the pump after the pump has been stopped and is again started.

With these constructions sufficient liquid is contained in the receptacle in casing 6, so that even though all the other liquid drains out of 40 or is sucked backwardly through the pump, the rotation of the motor and pump shaft 10 will discharge the liquid from the priming receptacle to form a liquid seal for the pump.

I claim:

45 1. A device of the character set forth comprising pump mechanism, rotary driving means for the pump mechanism, and means associated with the driving mechanism for catching a quantity of liquid which is delivered thereto by the pump when operating and for discharging the liquid therefrom into the discharge side only of the pump when the driving means is started.

53 2. The combination with a pump, of movable means for operating the pump, and a self primer comprising a receptacle adapted to receive liquid from the pump, the liquid being discharged from the receptacle into the pump for priming the same by the operating means when said operating means is started.

53 3. The combination with a pump and rotary means for driving it, of a self primer comprising a receptacle for receiving liquid discharged by the pump, the driving means being operative to discharge liquid from the

receptacle to provide a liquid seal for the discharge side of the pump when the pump is started.

4. The combination with a pump, of rotary operating means therefor, a receptacle 70 carried by the operating means for receiving liquid discharged from the pump, the liquid being discharged from the receptacle when the operating means is started and returning to the discharge side of the pump to form a 75 liquid seal therefor.

5. The combination with a pump, of a rotary driver therefor, a casing into which the pump discharges having an outlet above the bottom of the casing for obtaining a height 80 of liquid in the casing, a receptacle within the casing below the opening for receiving liquid and containing this liquid even though the remainder of the liquid in the casing passes outwardly through the pump, the liquid in the receptacle being discharged therefrom when the driver is first actuated and flowing to the bottom of the casing to provide a liquid seal at the discharge side of the 85 pump.

6. In a pumping system for drawing liquid from a distance and discharging it into a receptacle, a casing having an inlet at the bottom and a discharge at a distance above the bottom, a pump for drawing liquid from 90 a distance and discharging it through the bottom of the casing, rotary driving means extending through the casing and a priming device comprising a receptacle secured to the driving means and located in the casing below the discharge opening therefor to receive liquid pumped into the casing and to retain it therein when the pump is stopped, the liquid being discharged from the receptacle when the driving means is started after the 95 pump has been stopped and the liquid therefrom draining to the bottom of the casing to provide a liquid seal for the discharge side of the pump.

7. The combination with a pump, of means 100 for supplying a priming charge therefor at the discharge side of the pump and means actuated by the pump for discharging the charge into the pump chamber at the discharge side only as the pump is started. 105

JOHN T. JANETTE.
